DRAWING MACHINE

Wilhelm Stahl, Lahr, Germany, assignor to the
firm: Albert Nestler A.-G., Lahr, Germany

Application March 8, 1935, Serial No. 10,105
In Germany September 3, 1934

7 Claims. (Cl. 33—110)

The present invention relates to an apparatus for hatching drawings. The apparatus according to the invention is adapted for use in drawing machines of the kind at which the drawing head 5 can be moved over the drawing paper or the drawing board into any desired position.

By means of the novel apparatus the drawing head can be switched i. e. moved step by step in accordance with the distance between the dashes 10 or streaks of the hatching, by manipulating a switching device.

This switching or shifting is preferably performed by means of the main lever of the drawing head which controls the locking device. This 15 involves the advantage, that all movements of the operative parts of the drawing head can be performed by means of a single lever. It is hereby of importance that all parts influencing the locking members proper are held arrested during 20 the movements of the hatching device, so that the same are not moved together with the said main lever.

Two preferred constructional forms of the invention are shown by way of examples in the accompanying drawings.

Fig. 1 is a vertical section through the drawing head with the hatching apparatus in switched-off position.

Fig. 2 is a bottom view of the drawing head 30 shown in Fig. 1.

Fig. 3 is a vertical section through the drawing head with the hatching device in switched-in position.

Fig. 4 is a bottom view of the drawing head 35 shown in Fig. 3.

Fig. 5 is a vertical section through the drawing head after the line A—A in Fig. 2.

Fig. 6 is a vertical sectional view showing the 40 switching device of the drawing head in inoperative position.

Fig. 7 is a vertical sectional view showing a modified switching device in inoperative position.

Fig. 8 is a vertical sectional view showing the 45 switching device according to Fig. 6 in operative position.

Fig. 9 is a vertical section after line B—B in Fig. 3.

Fig. 10 is a section after line C—C in Fig. 2. 50 On the rails of a drawing machine a toothed disc 1 is fastened by means of screws 2 (Figs. 2 and 4). The disc 1 is formed with a sleeve 3 which serves as a pivot for a rule holder disc 4, the arms 5 and 6 of which are adapted to receive 55 the rules or measuring rules (not illustrated).

The discs 1 and 4 form together with accessories the drawing head proper. The rule holder disc 4 is prevented from sliding off the sleeve 3 by means of a ring 7 and a set-screw 8. In a casing 9 rigidly connected to the rule holder disc 4 a bolt 5 10 is fixed and this bolt is surrounded by a torsion spring 11 the leg 12 of which presses against a pin 13 on an angle lever 14 and strives to turn this lever in clockwise direction on its pivot 15. The lower side of the rule holder disc 4 is formed 10 with a guide 16 in which a slide 17 is located which by the torsion spring 11, under the intermediary of the arm 18 of the angle lever 14, is pressed radially against the toothed disc 1, whereby a projection or finger 19 on the slide 17 is 15 pressed into a space between the teeth of the disc 1 and the rule holder disc 4 is held securely against rotation.

When it is desired to alter the adjustment of the rule holder disc 4, this may be effected by 20 means of the lever 20. This lever is rotatably arranged on the pivot 15 and normally rests with its lower side against a projection 21 on the angle lever 14. When the lever 20 is turned in the direction of the arrow L it will take the angle 25 lever 14 along with it and the arm 18 of the latter lever will force the slide 17 out of engagement with the toothing on the disc 1. When the rule holder disc 4 by rotation has been brought into 30 its new position and the lever 20 is released, the slide 17 will automatically slide back into a space 35 between the teeth of the disc 1 (Figs. 1 and 2).

If it, for adjustment of the rule holder disc 4 between two teeth of the disc 1, is desired to keep the slide 17 out of engagement with the toothed 35 disc 1 for a longer time or permanently, the lever 20 is moved in the direction of the arrow R. Hereby the upper end of the lever 22, which is located in the casing 9 on a pivot 23, is taken along with the lever 20 in the same direction, 40 whereby simultaneously the lower arm 18 of the angle lever 14 is swung outward by the link 24 and the slide 17 is drawn out of engagement with the toothing of the disc 1 (Fig. 6).

On the lower side of the rule holder disc 4 a 45 clamping plate 89 is arranged, which contacts with the lower side of the toothed disc 1 and is formed or equipped with a pin 88, which projects into an aperture in the rule holder disc 4 (Fig. 10). A threaded pin 81, which is rigidly fixed to the clamping plate 89, projects through an opening in the rule holder disc 4 and carries a nut with a finger grip 82. When the nut is 50 drawn tight the toothed disc 1 and the rule holder 55

disc 4 are pressed together and are held against undesired rotation.

The hitherto described mechanisms of the drawing head are known per se and serve merely for adjusting the drawing head in the various angular positions relative to the horizontal plane.

In the following the hatching apparatus will be described. Also this apparatus is operated by the lever 20, independently of the mechanism already described.

On its lower surface the toothed disc 1 is formed with a boss 25 which in its centre has a T-shaped groove 26 in which a slide or switching member 27 is located. This slide is normally pressed against a stop 30 by one arm of a two-armed spring 29 which is wound on a pin 28. Perpendicular to the T-shaped groove 26 and parallel to the end face of the boss 25 a shallow groove 31 is formed in which two leaf springs 33 are located which by means of screws 32 are fixed to the lower side of the toothed disc 1. The free ends of these springs serve as supports for the slide 27 and normally hold the same in such a position, that its corrugated lower side lies at a higher level than the end face of the boss 25 (Fig. 1). In the sleeve 3 another vertically displaceable sleeve 34 is arranged which at its lower end is formed with a slot 35 in which a pin 36 is fixed which serves as a pivot for an angle lever 37 the downwardly directed arm 38 of which projects into an aperture 39 in the slide 27. At its upper end the sleeve 34 is formed with a flange 40 and between this flange and the ring 7 a pressure-spring 41 is located which strives to hold the sleeve 34 at so high a level that a free intermediate space is formed between the upper surface of the slide 27 and the lower end face of the sleeve 34, so that the slide, if required, may slide freely (Figs. 1 and 5). In the sleeve 34 a partially hollow plunger 42 is slidably arranged and this plunger is formed with a finger 43 which, when the plunger is depressed, will engage the arm 44 of the angle lever 37. The length of the stroke of the plunger 42 is limited by a pin 45 which is passed through the massive part of the plunger and which also prevents rotation of the plunger and the sleeve 34. The pin 45 is of such a length that it projects into the slots 46 and 47. Between the plunger 42 and the sleeve 34 a pressure spring 48 is located which strives to separate the plunger 42 and the sleeve 34, so that the pin 45 is pressed against the upper end of the slots 47. Hereby the pressure spring 41, which is weaker than the spring 48, will force the sleeve 34 upward together with all parts contained therein until the pin 45 is arrested at the upper end of the slot 46 (Figs. 1 and 5).

If now the plunger 42 is depressed by a force acting in the direction of the arrow P (Fig. 3) the spring 41 is compressed until the flange 40 of the sleeve 34 contacts with the upper end of the sleeve 3. Simultaneously the slide 27 is forced outward by the lower end of the sleeve 34 against the force of the leaf springs 33 until the corrugated lower surface of the slide 27, (which slide has an ample play in the T-shaped groove 26) protrudes over the lower end of the boss 25. Hereby the drawing head, which initially rested on the drawing board with the lower end of the sleeve 34, is lifted so that the drawing head now only rests on the drawing board with the corrugated lower face of the slide 27. The slide 27 is lightly clamped between the lower end of the sleeve 34 and the leaf springs 33. If the pressure on the plunger 42 is maintained in the direction of the

arrow P, the spring 48 will be compressed and the finger 43 of the plunger 42 will move the angle lever 37 in clockwise direction whereby the drawing head, which rests on the drawing board with the slide 27, is forced to make a corresponding movement in the direction of the slide (Figs. 3 and 4).

If the pressure on the plunger 42 is removed the spring 48 will force the plunger upward until the pin 45 is arrested at the upper end of the slots 47 in the sleeve 34. Thereupon the spring 41 will lift the sleeve 34 together with all parts contained therein until the pin 45 also settles in the slots 46. During the last part of the movement of the sleeve 34 the slide 27 is forced back into the T-shaped groove 26 by the leaf springs 33 so that the drawing head again rests on the drawing board with the lower end of the boss 25. The spring 29 thereupon forces the now fully released slide 27 back into its original position in which it is pressed against the stop 30.

The plunger 42 of the hatching device is preferably actuated by the same lever 20 which is used for adjusting the drawing head, because in this case the position of the hand and the movement of the thumb will be the same at all manipulations of the drawing head.

In order that the parts of the adjusting or arresting mechanism remain inoperative during the hatching operation the lever 20 is moved to the right in the direction of the arrow R into the position shown in Fig. 6. In this position the arm 49 of the angle lever 50, which latter is pivotally arranged on the pin 51 in the casing 9, can be swung past the nose 52 of the angle lever 14 in clockwise direction. The tip lever 55, which is pivotally arranged on the pin 54 fixed to the lever 53 partakes in this movement, whereby the position of the tip lever 55 in the space is so altered that its right end will take up a position below the nose 56 of the lever 20 (Fig. 6). If in this position the angle lever 50 is held stationary by means of the pivot 54 (which pivot projects beyond the casing 9) and the lever 20 is swung back to the left in the direction of the arrow L, then the nose 52 of the angle lever 14 will under the influence of the torsion spring 11 be pressed against the lever arm 49 and in this position the angle lever 14 and also the angle lever 50 are held arrested. 57 denotes a tip lever which consists of three arms 59, 60 and 62 and is carried by the pivot 58 fixed to the casing 9. The arm 59 of this lever contacts with the plunger 42 whereas the arm 60 is situated above the left end of the tip lever 55. If now the lever 20 is moved in the direction of the arrow L this movement is from the nose 56 transmitted to the plunger 42 over the tip levers 55 and 57.

The length of the stroke of the plunger or the distance between the lines in the hatchings is controlled by means of a spiral disc 61 on which the arm 62 of the lever 57 rests. The spiral disc is rotatably arranged on a pivot 64 which is fixed to the plate 63. The plate 63 is located in a seat formed in the handle 66 and is fixed to the same by means of screws 65. The handle 66 itself is fixed to the rule holder disc 4 by means of screws 67.

When it is desired to bring the hatching device into its inoperative position and to re-establish the original conditions the lever 20 is first turned to the right into the position shown in Fig. 6. Hereby the nose 52 releases the lever arm 49 and the spring 68 on the pin 51 forces the angle lever 50 to the left into its position of rest. Thereupon

the lever 20 is moved to the left in the direction of the arrow L, whereby all parts are brought back into the position shown in Fig. 1.

The Figs. 7 and 8 show a modified hatching device at which the slide 27 is replaced by a roller 67 having a toothed surface. This roller is rotatably arranged on a pin 70 which is carried by the forked end of a yielding lever 71. One end of the forked lever 71 is together with a brake spring 72 fixed to the lower surface of the toothed disc 1 by means of a screw 73. In inoperative condition the other end of the lever 71 rests on the bottom of the groove 74 in the boss 75. The brake spring 72 creates the necessary friction between the lever 71 and a segmental toothed lever 78 which is located in the sleeve 76 on a pivot 77. In its position of rest the segmental lever 78 is pressed against a stop 86 by a torsion spring 79. The segmental lever is like the slide 27 actuated by the plunger 42.

When the plunger 42 is depressed the segmental lever engages the toothing of the roller 69 and forces the latter out of the boss 72, so that the drawing head thereupon rests on the drawing board with the roller 69. During the continued movement of the plunger 42 the roller 69 is rotated, whereby the drawing head is displaced correspondingly.

Further embodiments, modifications and variations may be resorted to within the spirit of the invention as here claimed.

I claim:

1. In the drawing head of a drawing machine, in combination, a rule holder, means for adjusting said rule holder, other automatically operating means for locking the rule holder in the adjusted position, a hatching device comprising a switching mechanism for moving the drawing head a predetermined distance corresponding to the chosen distance between the lines of the hatching, and still other common means for actuating said adjusting means and said hatching device.

2. In the drawing head of a drawing machine, in combination, a rule holder, means for adjusting said rule holder, other automatically operating means for locking the rule holder in the adjusted position, a hatching device comprising a switching mechanism for moving the drawing head a predetermined distance corresponding to the chosen distance between the lines of the hatching, and a single lever for actuating said adjusting means and said hatching device.

3. In the drawing head of a drawing machine, in combination, a rule holder, means for adjusting said rule holder, other automatically operating means for locking the rule holder in the adjusted position, a hatching device, comprising a spring-supported switching member, the lower surface of which normally lies in a higher horizontal plane than the lowermost surface of the

rule holder, an axially displaceable sleeve arranged within the drawing head, operating means for the switching member arranged in said sleeve, a spring-controlled plunger for actuating said switching member, a spring for holding said sleeve in raised position, and a single lever for actuating said adjusting means and said hatching member.

4. In the drawing head of a drawing machine, in combination, a rule holder, means for adjusting said rule holder, other automatically operating means for locking the rule holder in the adjusted position, a hatching device, for moving the drawing head a predetermined distance corresponding to the chosen distance between the lines of the hatching, a single lever for actuating said adjusting means and said hatching device, said hatching device comprising a switching member, a plunger adapted to bring the switching member into engagement with the paper, and to move the drawing head over the predetermined distance, and an intermediate lever system for transmitting the movements of said lever to the said plunger.

5. In the drawing head of a drawing machine, in combination, a rule holder, means for adjusting said rule holder, other automatically operating means for locking the rule holder in the adjusted position, a hatching device, for moving the drawing head a predetermined distance, a single lever for actuating said adjusting means and said hatching device, said hatching device comprising a switching member, a plunger adapted to bring the switching member into engagement with the paper and to move the drawing head the predetermined distance, an actuating lever for said plunger, and adjustable means for controlling the movement of said actuating lever.

6. In the drawing head of a drawing machine, in combination, a rule holder, means for adjusting said rule holder, other automatically operating means for locking the rule holder in the adjusted position, a hatching device, for moving the drawing head a predetermined distance, a single lever for actuating said adjusting means and said hatching device, said hatching device comprising a switching member, a plunger adapted to bring the switching member into engagement with the paper and to move the drawing head the predetermined distance, an actuating lever for said plunger, and a rotatable disc with a spiral-shaped edge for controlling the movement of said actuating lever.

7. In the drawing head of a drawing machine, a rule holder, means for adjusting said holder, a hatching device, means for operating said adjusting means as well as said hatching device, and an interlocking lever system adapted to lock said adjusting means when the hatching device is operated.

WILHELM STAHL.
